UNITED STATES PATENT OFFICE.

JESSE THOMAS CARNEY, OF RIO DE JANEIRO, BRAZIL.

CHAIR OR SOCKET FOR THE RAILS OF RAILWAYS AND THE LIKE.

1,156,754.

Specification of Letters Patent.

Patented Oct. 12, 1915.

Application filed July 29, 1914. Serial No. 853,928.

To all whom it may concern:

Be it known that I, JESSE THOMAS CARNEY, citizen of the United States of America, residing at Rio de Janeiro, Brazil, have invented certain new and useful Improvements in Chairs or Sockets for the Rails of Railways and the like, of which the following is a specification.

This invention refers to chairs or sockets for the rails on railroads and the like and especially to chairs of the kind designed for fixing on to sleepers which are possessed of a vertical plate and the means of supporting this plate in a vertical position, for example, of sleepers consisting of a vertical plate on which side-flanges are formed to support such plate in a prismatic triangular block of concrete, molded around the said plate and described in my application for Letters Patent filed June 10, 1914, Serial No. 844,222, renewed April 30, 1915, Serial No. 25050.

The invention consists of the improvements herein below described and illustrated in the accompanying drawings, in which—

Figure 1 is an elevation partly broken away of a sleeper having a rail and chair applied thereto, the rail and chair being shown in section, the section being on line 1—1 of Fig. 2. Fig. 2 is a sectional view of the same on line 2—2 of Fig. 1. Fig. 3 is a sectional view on an enlarged scale of the chair shown in Figs. 1 and 2, the section being on line 3—3 of Fig. 4. Fig. 4 is a sectional view of the same on line 4—4 of Fig. 3. Fig. 5 is a side elevation of a modified form of chair to which the rail is shown applied, Fig. 6 is a sectional view of the same on the line 6—6 of Fig. 5, Fig. 7 is a sectional view of another modified form of chair, the section being on line 7—7 of Fig. 8, Fig. 8 is a sectional view of the same on the line 8—8 of Fig. 7, Fig. 9 is a sectional view of another modified form of chair, the section being on line 9—9 of Fig. 10, Fig. 10 is a sectional view of the same, on line 10—10—of Fig. 9 and Fig. 11 is a plan view of the same.

In the course of this description, the terms "lengthways" and "cross-wise" should be understood as relating to the longitudinal and transversal sense, respectively of the railway-track.

In the drawings T indicates the rail, U the sleeper and W the chair for the rails.

The chair represented in Figs. 1 to 4, has two vertical flanges A¹, A², between which a groove B is formed for the purpose of receiving the upper part of the vertical plate B' of the sleeper on to which the chair is fixed. The bottom of this groove ought to be oblique in relation to the lay of the rail, so that this lay remains inclined in a transversal sense, in such a manner that the base of the rail possesses the usual inclination desirable, in its position relative to the axis of the railway track. In the said flanges A¹, A² are the necessary holes C, for screws or rivets, by means of which the chair is fixed on to the vertical plate of the sleeper. The width of this chair is the same as the width of the lower part of the rail T (Figs. 1 and 4) and its length is, more or less, equal to its breadth or width, preferably a little more. The upper surface of the chair is not flat, although it is composed of a cylindric concave surface whose generatrices are parallel, in a cross-wise sense with the chair and therefore the opposite longitudinal faces of the chair are bounded on the upper part by a concave circular surface as indicated. The chair in Figs. 1 to 4 is elastic and made of sheet iron or steel. The rail T is fastened on to this chair by two braces or metallic clamps G, G' which pass respectively below the extremity of the chair and the ends of each clamp are doubled over the opposite sides of the lower part of the rail.

In Figs. 1 and 4 the clamp is represented as doubled over and fastened on tight to the opposite sides of the bottom of the rail. Preferably and as may be seen by Fig. 3, the clamp is made of round iron strips flattened on one side and possessed of the requisite strength, and these clamps can be made previously with one end doubled over and the other to be doubled afterward. At each extremity of the lower face of the chair there is a frieze—F, which prevents the respective clamp from getting out of its place externally. The dislocation of the clamp internally is prevented by the curved shape of the lower face of the chair which descends in an oblique manner to the flanges A¹, A². So long as it has no weight to support, the rail rests solely upon the transversal supports at the ends of the chair, but when the rail is called upon to bear the weight, say, of a passing train, the chair, due to its elastic properties yields and its upper face enters into contact with the lower face

or base of the rail, totally or partially according to the pressure of the said weight.

Figs. 5 and 6 show a chair with two flat longitudinal seats for the lower face of the 5 opposite sides of the base of the rail. Between those two seats in the chair there is a void space so that the rail may yield in an elastic manner to the pressure of the load, supporting itself upon the said side seats.

10 A^1, A^2 are lower vertical flanges and B , the groove between these flanges, these elements correspond to the elements of the chair in the Figs. 1 to 4, indicated by the same letters. On the smooth upper face of 15 the chair a longitudinal canal D is formed a little broader than the half of the width of the base of the rail T , which rests by the opposite sides of its lower face on the two parts of the smooth upper face of the chair 20 separated by the said canal. The rail is held in the chair by an indented jaw-clasp M formed in one of the sides of the chair and by a containing block N fixed on to the chair by a screw N^1 .

25 Figs. 7 and 8 show a chair in which the seat for the rail is composed of a convex cylindrical surface with the generatrices placed cross-wise upon the rail, by which the lower face of the base of the rail comes 30 in contact with one only of the generatrices of the said cylindrical surface. On a rail supported on chairs of this description, the vibrations produced by a train passing over it are distributed from one extreme to the 35 other of the rail with much greater facility and regularity than when the rail is supported on chairs with seat lengthwise, and thus the rail suffers less and lasts longer. In these figures A^1, A^2, B are elements similar to these indicated by the same letters in 40 the Figs. 1 to 6. The said cylindrical seat is indicated at S ; M is an indented jaw-clasp formed in the chair, and N is a block for stoppage fixed on to the chair by a screw 45 N^1 ; this stop-block co-operates with the indented jaw-clasp M to secure the rail upon the chair.

50 Figs. 9, 10, and 11 show a chair with a recess in which a cushion of material adapted for 55 deadening shocks is placed; the rail reposes exclusively upon this cushion which deadens all the shocks received by the rail. This chair has parallel vertical flanges A^1, A^2 , separated by a groove B , like the chairs described above. This chair has a recess upon the upper face with four triangular walls having a vertex V common to all four. This recess serves as the socket for the lower part 60 of a cushion E' in the shape of an octagon or of two quadrangular pyramids united in one common base. This cushion may be made of an animal or vegetable fiber mixed with asphalt in order to prevent putrefaction and molded into the said shape under 65 very strong pressure (of from 10 to 50

tons). Or the cushion may be made of lead or of a mixture of lead, or may be made of any other material capable of deadening shocks. The lower pyramid of this cushion rests embedded in the already-mentioned 70 recess of the chair. The rail is placed on the upper vertex of the cushion, however after the passing of any trains the cushion receives a final compression and its upper part remains a little flattened as shown in 75 Figs. 9 and 10. It is evident that the cushion may have any other shape adequate to the purposes of the invention, calculating however that after the final compression by the passing of trains over it the rail remains 80 resting on the cushion exclusively and not on any other part of the chair. The recess in the chair shall be of a shape corresponding to the lower part of the cushion.

In order to maintain the rail in the chair 85 an indented clip M is shown in Figs. 10 and 11 formed in the chair and a stop-block N fixed on to the chair by a screw N^1 . In place of the indented clip M and the block N in the three chairs of Figs. 5 to 11, one 90 may employ any other means that may be adequate for maintaining the rails upon these chairs.

Having thus described my invention, I claim—

95

1. A chair, preferably of wrought iron or steel for rails and which has two vertical parallel flanges for fixing it on to the vertical plate of a sleeper characterized by having a cylindrical or similar convex surface 100 with the generatrices in a cross-wise sense of the rail which rests solely upon one of these generatrices and not upon any other part of the chair.

2. A chair for rails having vertical parallel flanges for securing the same to the vertical plate of a sleeper, the chair having a cylindrical or similar convex surface on which the rail rests, an indented jaw-clasp formed on the chair, and a stop block affixed 110 to the chair by screws and co-operating with the said jaw clasp to hold the rail in its place upon the said chair.

3. A chair for rails having downwardly extending spaced vertical parallel flanges 115 forming a groove between the same, to receive a member of a sleeper, the bottom of said groove being oblique in a direction cross-wise of the rail, the flanges being provided with perforations for securing the 120 same to said member of the sleeper, and means for holding the rail in position on the chair.

4. The combination with a rail, a sleeper having a vertical plate, and a metal chair 125 for the rail having two vertical flanges for securing the chair on the vertical plate of the sleeper, the flanges forming a groove between them to receive the said vertical plate, the bottom wall of said groove being 130

oblique in a direction crosswise of the rail, of means engaging the rail to hold the same on the chair.

5. The combination with a rail, a sleeper having a vertical plate, and a metal chair for the rail having its upper face provided with a surface on which the rail is adapted to rest, the said chair having two downwardly extending vertical parallel flanges 10 and a groove between the flanges to receive the upper part of the vertical plate of the sleeper, the bottom wall of the said groove being inclined in a direction cross-wise of the rail, means for securing the flanges and the said plate together and means for holding the rail in place on the chair.
6. The combination with a rail, a sleeper

having a vertical plate, and a chair for the rail having a convex cylindrical upper surface extending crosswise of the rail and on 20 which the rail is adapted to rest throughout its width, the said chair having two downwardly extending parallel flanges for securing the chair to the vertical plate of the sleeper, and means at the ends of the chair 25 and engaging the rail to secure the same to the chair.

In testimony whereof I have hereunto set my hand in presence of two subscribing witnesses.

JESSE THOMAS CARNEY.
